UNITED STATES PATENT OFFICE.

GEORGE D. KINSEY, OF BROOKLYN, NEW YORK, ASSIGNOR TO THE AUSTRALIAN KNITTING COMPANY, OF PATERSON, NEW JERSEY.

DESIGN FOR A KNITTED FABRIC.

SPECIFICATION forming part of Design No. 19,664, dated February 25, 1890.

Application filed January 21, 1890. Serial No. 337,657. Term of patent 7 years.

To all whom it may concern:

Be it known that I, GEORGE D. KINSEY, of Brooklyn, in the county of Kings and State of New York, have invented and produced a new and original Design for Knitted Fabrics, of which the following is a specification.

The accompanying drawing illustrates a design embodying my invention, the design being shown in the black portions of the figure.

The design consists, essentially, of substantially parallel lines A, constituting the side edges of the design. Extending from both sides of the lines A are substantially straight portions $a a'$, said portions $a a'$ being zigzagged relatively to each other. The portions $a a'$

of one of the lines A are substantially opposite the spaces between the portions $a a'$ of the other line A. Intermediate of the lines A and portions $a a'$ are diagonally-extending figures B, which figures are separated from each other and terminate at their upper and lower ends in substantially rectangular figures b.

What I claim as my design is—

A design for a knitted fabric, substantially as herein shown and set forth.

GEORGE D. KINSEY.
